BOOM HEAD

Ernest W. Taylor and Peter Nielsen, Bay City, Mich., assignors to Industrial Brownhoist Corporation, Bay City, Mich.

Application January 31, 1944, Serial No. 520,506

2 Claims. (Cl. 212—144)

This invention relates to booms of the type used on cranes, excavators, and mechanism of similar character, and more particularly to the boom head and the arrangement and mounting of the various reeving sheaves thereon.

One of the prime objects of the invention is to design a boom head for cranes and heavy material handling equipment of a similar nature in which any one of the rope sheaves and its companion pin can be quickly and easily removed when not in use and replaced when the nature of the work requires.

Another object is to provide a boom head arrangement in which the back stay is independent of the sheave pins so that the sheaves and pins can be removed, replaced, and/or rearranged without in any manner affecting the back stay or the stay rope support for the boom.

A further object is to provide a boom head in which the sheaves are mounted at longitudinally spaced points, depending on the load and radius, so that the boom can be made much narrower, effecting a saving in weight and material, and the reeving being such that there will be no reverse bends in the line.

Still a further object of the invention is to design a boom head from which the individual sheave assemblies can be readily removed or added as required by the nature of the work to be accomplished, thereby eliminating excessive weight and affecting a saving in the power required for operation.

The invention may be more fully understood from the following detailed description and explanation referring to the accompanying drawings illustrating the preferred embodiment of the invention.

Fig. 1 is a side elevation view of a boom head embodying our invention.

Fig. 2 is a top plan view;

Fig. 3 is a view similar to Fig. 1 and showing an extension secured to the end of the boom;

Fig. 4 is a top plan view thereof, the sheaves being omitted.

Fig. 5 is an enlarged transverse sectional view taken on the line 5—5 of Fig. 3.

Referring now more particularly to the drawings in which we have shown one embodiment of our invention, the letter "B" indicates a conventional boom which can be of any desired design, the lower end being hingedly connected to a crane or excavator (not shown), and is pivoted for swinging movement in a vertical plane.

In the present instance the boom is shown as constructed of angles 10 suitably reinforced by

latticing 11 to form a rigid structure. Vertically disposed plates 12 and 13 form a part of the boom head and are welded or otherwise secured to the side walls of said boom, these plates projecting above and below the boom proper, and strips 14 are welded to the side walls of the plates to further reinforce the structure. Bearing blocks 15 are welded to the inner face of the angles 10 and as clearly shown in Fig. 5 of the drawings, and plates 16 and 17 respectively are secured to the top and bottom of the boom, these plates being cut away as at 18 to accommodate the reeving sheaves as will be hereafter described.

A plurality of openings 19, 20 and 21 are provided in the boom head, and sheave pins 22 and 23 are mounted therein; sheaves 24 and 25 being mounted on the pin 22, and a similar sheave 26 is mounted on the pin 23, any sheave and its companion pin being readily shiftable for mounting in the opening 21 when desired.

A boom stay pin 27 is mounted in openings 28 provided in the upper edges of the side plates and the rope 29 is anchored thereto in the conventional manner.

25 The sheave pins can be secured in position in any approved manner, the instant design showing a plate 30 welded to one end of the pin, this plate covering the opening 19 and butting against the member 31, which is welded to the side plate 12. A similar member 32 is welded to the opposite plate 13, and a detachable plate 33 is secured to this end of the pin by means of bolts 34, all as shown in Fig. 5 of the drawings, and when it is desired to remove the pin, it is merely necessary to remove the bolts 34 and the pin can then be shifted endwise from the boom head.

Heretofore, when handling maximum loads with six parts of line, it has been customary to mount the three sheaves 24, 25 and 26 side by side on a pin with the back stay for the boom attached to the same pin, consequently, it was necessary to remove the back stay in order to remove any one or more of the sheaves, and it was also necessary to make the boom sufficiently wide to accommodate the sheaves side by side.

In the instant arrangement, the back stay pin is separate and independent, and there are three separate points on the boom for pinning the sheaves, with this arrangement, and when handling maximum loads at minimum radius, we place the sheaves 24, 25 and 26 as indicated in Figs. 1 and 2 of the drawings, inasmuch as the maximum load can be handled only at the minimum radius and the loading is such that at maximum radius it requires one sheave only, there-

fore it will be obvious that considerable weight can be eliminated by removing the two sheaves 24 and 25.

Under certain conditions where minimum load is to be handled at maximum radius, it is advantageous to provide a boom extension "E" as clearly shown in Figs. 3, 4 and 5 of the drawings, such extension being of the same general construction as the main body of the boom and is held in place by means of bolts 35. Horizontally aligned openings 36 are provided in the side walls of said extension and accommodate the sheave pin 37 on which the sheave 38 is journaled, with such arrangement it is possible to use one drum (not shown), of the crane as a main hoist, and one drum (not shown), as an auxiliary hoist, thus making provision for handling both light and heavy loads with a minimum number of parts of line.

This design makes it possible to easily remove the sheave assemblies not in use, and eliminates the weight represented thereby, thus conserving power, making it possible to lighten the boom proper, and to remove or replace sheaves without affecting the stay pin or otherwise supporting the boom while changes are being made.

From the foregoing description it will be obvious that we have perfected a simple, practical,

economical boom head arrangement for cranes and excavating equipment in general.

What we claim is:

1. In a boom for cranes and similar apparatus, the combination at the head end of the boom, of vertically disposed side plates projecting above and below said boom and rigidly secured thereto, horizontally aligned sheave pin openings in said plates in staggered, longitudinally spaced relation, quickly removable sheave pin and sheave assemblies mounted in said openings, and an individual stay pin removably mounted in the upper section of said plates.

2. In a boom for cranes and similar apparatus, the combination at the head end of the boom, of vertically disposed side plates extending above and below said boom and rigidly secured thereto, horizontally aligned sheave pin openings in said plates in staggered, longitudinally spaced relation, quickly removable sheave pin and sheave assemblies mounted in said openings, an individual stay pin removably mounted in the upper section of said plates, a boom extension detachably attached to the end of the boom beyond said plate members, and a sheave assembly journaled on said extension.

ERNEST W. TAYLOR.
